UNITED STATES PATENT OFFICE.

JOHN BROCH, OF CORONA, NEW YORK.

DESIGN FOR A HATRACK.

Application filed June 11, 1928. Serial No. 27,079. Term of patent 3½ years.

To all whom it may concern:

Be it known that I, JOHN BROCH, a subject of the King of Spain, residing at Corona, L. I., in the county of Queens, and State of New York, have invented a new and original Design for a Hatrack, of which the following is a specification, reference being had to the accompanying drawing, forming part thereof.

Fig. 1 is a front elevational view of a hat rack showing my new design.

Fig. 2 is a side view of same.

Fig. 3 is a plan view of same.

I claim:

The ornamental design for a hatrack as shown.

In testimony whereof I have affixed my signature.

JOHN BROCH.
